US0D1108416S

(12) **United States Design Patent** (10) **Patent No.:** **US D1,108,416 S**
(45) **Date of Patent:** ** **Jan. 6, 2026**

(54) **LAPTOP COMPUTER**

(71) Applicant: **Lenovo (Beijing) Limited**, Beijing (CN)

(72) Inventor: **Peiyin Yang**, Beijing (CN)

(73) Assignee: **Lenovo (Beijing) Limited**, Beijing (CN)

(**) Term: **15 Years**

(21) Appl. No.: **35/521,141**

(22) Filed: **Apr. 17, 2024**

(80) **Hague Agreement Data**

Int. Filing Date: **Apr. 17, 2024**

Int. Reg. No.: **DM/237369**

Int. Reg. Date: **Apr. 17, 2024**

Int. Reg. Pub. Date: **Jun. 7, 2024**

(30) **Foreign Application Priority Data**

Oct. 24, 2023 (CN) 202330690695.0

(51) **LOC (15) Cl.** **14-02**

(52) **U.S. Cl.**

USPC **D14/316**

(58) **Field of Classification Search**

USPC D14/315-327, 345, 432-434, 439-440,
D14/224-224.1, 451; D8/323

(74) *Attorney, Agent, or Firm* — SYNCODA LLC; Feng Ma

(57) **CLAIM**

The ornamental design for a laptop computer as shown and described.

DESCRIPTION

1. Laptop computer
- 1.1 : Front; closed
- 1.2 : Back; closed
- 1.3 : Left; closed
- 1.4 : Right; closed
- 1.5 : Top; closed
- 1.6 : Bottom; closed
- 1.7 : Perspective; closed
- 1.8 : Front; open in first configuration of use
- 1.9 : Back; open in first configuration of use
- 1.10 : Left; open in first configuration of use
- 1.11 : Right; open in first configuration of use
- 1.12 : Top; open in first configuration of use
- 1.13 : Bottom; open in first configuration of use
- 1.14 : Perspective; open in first configuration of use
- 1.15 : Perspective; open in second configuration of use
- 1.16 : Perspective; open in third configuration of use

(Continued)

The broken lines shown in the drawings illustrate portions of the laptop computer that form no part of the claimed design.

1 Claim, 9 Drawing Sheets
